(57) **CLAIM**

I claim the ornamental design for a glucometer, as shown and described.

DESCRIPTION

FIG. 1 is a perspective view of a glucometer my design;

FIG. 2 is a front view of the glucometer;

FIG. 3 is a rear view of the glucometer;

FIG. 4 is a left side view of the glucometer;

FIG. 5 is a right side view of the glucometer;

FIG. 6 is a top plan view of the glucometer; and,

FIG. 7 is a bottom view of the glucometer.

The broken lines in each of the figures showing a portion or portions of the glucometer are for illustrative purposes only and form no part of the claimed design.
